(57) **CLAIM**

The ornamental design for an adapter for an insulator, as shown and described.

DESCRIPTION

1.1 : is a top view of showing the new design;
 1.2 : is a right perspective view of showing the new design;
 1.3 : is a bottom right perspective view of showing the new design;
 1.4 : is a rear right perspective view of showing the new design;
 1.5 : is a left perspective view of showing the new design;
 1.6 : is a front view of showing the new design;
 1.7 : is a right side view of showing the new design.
 The broken lines in FIGS. 1.1-1.7 illustrate unclaimed subject matter and do not form any part of the claimed design.
